(57) **CLAIM**

We claim the ornamental design for a gas burner for stoves, as shown and described.

DESCRIPTION

FIG. 1 is a perspective view of a gas burner for stoves showing our new design.

FIG. 2 is a top planform view thereof.

FIG. 3 is a bottom planform view thereof.

FIG. 4 is a right side elevational view thereof.

FIG. 5 is a left side elevational view thereof.

FIG. 6 is a front elevational view thereof; and,

FIG. 7 is a rear elevational view thereof.

The broken lines depict portions of the gas burner that form no part of the claim.
